2,064,926

REFRIGERATOR

Chester A. Kuebler, Eric, Pa.

Application November 29, 1933, Serial No. 700,232

8 Claims. (Cl. 62—89)

This invention pertains to refrigerators and more particularly to refrigerators adapted for domestic or similar uses.

The conventional type domestic refrigerator comprises a unitary cooling chamber, all parts of which are maintained at substantially the same temperature, neglecting a slight variation in temperature between the top and bottom portions of the chamber due to convection by air currents.

Various food stuffs stored in the chamber are necessarily subjected to the same conditions of temperature and humidity whereas it is found that for most efficient and economical preservation of food stuffs that differing conditions of temperature and humidity should be provided. For example, meat to be properly preserved requires a lower temperature than eggs, vegetables and various fruits. Again, the coils of the evaporator or cooling unit absorb moisture from the air in the chamber and this renders vegetables containing a large amount of water, such as lettuce, celery, spinach etc. and various fruits too dry to be properly edible.

I have devised an improved refrigerator having a horizontally movable drawer disposed in a chamber adjacent to and in communication with a main cooling chamber, and the air therein may be maintained at a relatively higher temperature than in the main chamber and at a greater degree of humidity, thereby solving the problem hereinbefore described of maintaining food stuffs at different conditions of temperature and humidity.

The horizontal cooling drawer is movable outwardly from the refrigerator cabinet and thus permits all the articles disposed therein to be easily viewed and to be accessible without projecting an arm into the interior of the cooling chamber and without moving numerous other articles to obtain a desired article.

Furthermore, such a construction effects a considerable economy of operation since it is not necessary to expose the entire cooling chamber to external room temperature by opening the chamber door when it is desired to secure frequently used articles or food stuffs. The cold air in a cooling chamber being disposed at the bottom of the chamber will immediately drop to the floor and be replaced by warm air upon opening of the chamber door, and by my improved construction the necessity for opening the door to the main cooling chamber is relatively infrequent.

It is an object of my invention therefore to

provide a refrigerator having cooling chambers subjected to differing conditions of temperature and humidity.

Another object of my invention is to provide a refrigerator which is relatively economical to operate.

Another object of my invention is to provide a more convenient and accessible disposition of articles in a refrigerator than has heretofore been provided.

Another object of my invention is to provide an auxiliary cooling drawer for refrigerators subjected to a relatively higher temperature than the main cabinet and adapted to be supportingly moved outwardly from the cabinet.

Another object of my invention is to provide an improved refrigerator means for maintaining vegetables and the like in a crisp condition and which is more conveniently accessible than prior crisping chambers.

These and other objects of my invention will become increasingly apparent from a consideration of the following description and drawings, wherein:

Fig. 1 is a front elevational view of a refrigerator incorporating a preferred embodiment of my invention;

Fig. 2 is a horizontal sectional view taken along lines 2—2 of Fig. 1;

Fig. 3 is a medial vertical sectional view taken along the lines 3—3 of Fig. 1;

Fig. 4 is an enlarged detail view of latch mechanism which I may employ shown in a locking position;

Fig. 5 is a detail view of the latch mechanism of Fig. 4 shown in an unlocked position;

Fig. 6 is a perspective view of a modified type of drawer which I may employ;

Fig. 7 is an elevational view of a modification of my invention similar to the embodiment illustrated in Figs. 1, 2 and 3 but applied to a refrigerator of the top-mounted compressor unit type;

Fig. 8 is an elevational view of a further modification of my invention as applied to a top-mounted compressor type refrigerator;

Fig. 9 is a sectional view taken along the line 9—9 of Fig. 8;

Fig. 10 is a fragmentary sectional view taken along lines 10—10 of Fig. 3; and,

Fig. 11 is a fragmentary view taken along lines 11—11 of Fig. 9.

Referring now to the drawings, I have indicated generally at 1, Fig. 1, a refrigerator cabinet provided with a conventional compressor unit 2

mounted at the bottom of the cabinet, a main cooling chamber 3 disposed above the compressor unit, and a conventional evaporator unit or cooling unit 4 disposed within the chamber 3 and 5 preferably secured to the upper wall of the chamber.

The means employed to cool chamber 3 or the location of such means relative to the chamber constitutes no essential part of my invention and 10 it is understood that any desired means or relative location may be employed.

The walls of chamber 3 as best illustrated in Figs. 2 and 3 are suitably insulated and are preferably internally lined with sheet metal or the 15 like.

In my improved construction I provide an auxiliary chamber 5 adjacent to and beneath the chamber 3 by extending the back wall 6 downwardly a distance equal to the desired height of 20 the auxiliary chamber to meet a base 7 which is projected forwardly to the front face of the cabinet. Disposed horizontally across the front face of the cabinet and terminating in the side walls thereof is a bar 8, the bar 8 being spaced 25 upwardly from base 7 a distance equal to the desired height of chamber 5 and is preferably of a cross-sectional contour as illustrated in Fig. 2. The bar 8 is adapted to act as an abutting surface for the bottom portion of a peripheral sealing flange affixed to the external face of 30 a door 9 which forms a closure member for chamber 3.

In my preferred construction, the sheet metal or the like lining is carried horizontally from the 35 bottom face of the bar 8 to the rear wall 6, thereby forming a partition 10 intermediate chambers 3 and 5.

Disposed within chamber 5 is a generally box-shaped drawer 11 preferably formed of sheet metal, open at the top and lined at the front face of the drawer with insulating material of suitable thickness as indicated at 12. The outer face of drawer 11 comprises a generally rectangular shaped preferably sheet metal element 13 extending peripherally beyond the drawer proper a sufficient distance to effect a sealing engagement with the front face of the refrigerator. I preferably provide a peripheral strip of suitable sealing material on the inner face of element 13 as indicated at 14 to insure an effective seal when the drawer is in a closed position.

The element 13 has secured thereto a suitable handle 15 whereby the drawer may be moved outwardly and inwardly relative to the cabinet.

To effect easy operation of the drawer 11, I 55 preferably provide rollers 16 affixed to drawer 11 adjacent the rear wall thereof and so as to engage the top and bottom walls of chamber 5, and I preferably provide four such rollers, two on each side of the drawer. I also recess base 7 adjacent the front face of the cabinet to provide suitable mounting for rollers 17 adapted to engage the under side of drawer 11. The drawer may thus be easily moved without any danger of binding; and to prevent accidental removal of the drawer 60 completely from the chamber, I may provide stops 18 inserted in the under side of bar 8 spaced so as to engage top rollers 16. The drawer may be removed for cleaning purposes and the like by 65 moving it outwardly and tilting the outer end upwardly so that rollers 16 may clear stops 18.

In order to maintain the drawer 11 in sealing engagement with the cabinet when in a closed position, I provide a recess in back 6 and secure 70 therein an upstanding lip 20 and provide a latch

mechanism comprising a generally U-shaped mounting for a roller 21, the mounting being integrally secured to the rear wall of drawer 11 and the roller being adapted to engage a notched portion of a generally heart-shaped latch element 21a. The latch element 21a is pivotally mounted 5 as indicated at 22 and so as to engage roller 21. Secured to the latch element 21a intermediate the pivot 22 and the roller-engaging notched portion is one end of a tension spring 22a, the opposite spring end being secured to the base of the recess in any suitable manner and in such a position relative to the pivot 22 that, as illustrated in Fig. 4, it will urge the latch element 21a in a counter-clockwise direction to maintain the 10 drawer sealed and when the drawer is moved outwardly the latch element will be urged in a clockwise direction and maintained in abutting relation with lip 20 and in a position to re-engage roller 21. There is thus provided a simple and 15 positive latching mechanism for maintaining the drawer in a sealed position.

The partition 10 is provided with cooling slots as indicated at 23, affording communication with the cold air current in chamber 3. These slots 25 are preferably positioned adjacent the side walls of the cabinet as illustrated since the normal direction of the current as viewed in Fig. 1 would be downwardly from the base of the evaporator unit as the air is cooled, thence along the base 30 of the chamber 3 in a direction toward the left, and thence upwardly and along the top of the chamber to the evaporator unit; and by thus positioning the slots, advantage may be taken of the direction of air current to effect movement 35 of cooling air through chamber 5.

To control the relative amount of cooling air moving through chamber 5, I provide individually operable covers for the slots, the covers 40 preferably comprising rectangular sheet metal strips 23 slidably positioned intermediate grooves formed by partition 10 and relatively narrow strips indicated at 24 and secured to the lining in any suitable manner such as welding.

Although I have chosen to illustrate the control means as being individually operable, I contemplate that they may be jointly operable and further that they may be automatically operable responsive to thermostatic means disposed within chamber 5.

As previously described, these cooling air currents have a tendency to absorb moisture from vegetables and fruits containing a high percentage of water, and deposit the moisture on the coils of the evaporator unit. This not only tends 55 to render such vegetables and fruits excessively dry and beyond a desirable point, but the moisture deposited upon the coils acts as an insulating medium preventing efficient refrigeration and necessitating more frequent defrosting of the 60 coils. By controlling the rate and quantity of air currents, this dehydrating process can be reduced to a desirable point and such vegetables and the like maintained in a crisp condition.

Although the embodiment of my invention as 65 described acts as a crisping chamber, it may be desirable to limit the dehydrating effect to a still greater degree without raising the temperature to which eggs and the like stored in the drawer are subjected, and in the drawer illustrated in Fig. 6 I provide a central partition 30, preferably formed of sheet metal, and additional partitions 31 formed of wire mesh in one of the two compartments thus formed. The central 70 75

partition 30 is provided with ports as indicated at 30a.

Compartment 32 of the drawer may be utilized as the crisping chamber for vegetables and the like since cooling air currents will not pass therethrough as readily as compartment 32a. I contemplate also that additional individually controllable ports may be positioned in partition 10 adjacent to and on either side of partition 30 to variably control the dehydrating and cooling effect of air currents traversing compartments 32 and 32a. Compartment 32 may be provided with a suitable cover for enclosing the vegetables and the like.

Referring now to Fig. 7, I have shown my invention as applied to a refrigerator of the top-mounted compressor type, the compressor unit indicated at 45 being disposed above the main cooling chamber 3. This modification is similar to that illustrated in Figs. 1, 2 and 3, and I prefer that the drawer be positioned at substantially the same height from the floor and that to compensate for the top mounting that the height of the refrigerator be increased or the base of the main cabinet be raised. Otherwise the construction and operation is similar to the embodiment illustrated in Figs. 1, 2 and 3.

Referring now to Figs. 8 and 9, I have illustrated a still further modification of my invention as applied to a refrigerator of the top-mounted compressor type and wherein the auxiliary chamber as indicated at 50 is disposed intermediate the compressor unit 51 and the main cooling cabinet 3. I preferably provide vertical sheet metal guide strips 52—52 secured to the base of the chamber 50 and spaced inwardly from the chamber side walls which perform the dual function of acting as a guideway for drawer 54 and directing air currents entering the chamber through ports 55 over to the top of the drawer, the air currents being drawn from the chamber through ports 56.

Drawer 54 is similar to drawer 11 and a similar sealing and latching means is provided therefor. The ports 55 and 56 are disposed intermediate guide strips 52 and the chamber side walls and in a preferably sheet metal base 57 of chamber 50. The ports 55 and 56 are individually controllable by slidably strips 58 as previously described in connection with Figs. 1, 2 and 3.

It should be noted that the direction of cooling air currents in the main cabinet is such as to draw air downwardly from auxiliary cabinet 54 through ports 56 into the main cabinet.

In the various embodiments I have chosen to illustrate the auxiliary chamber as being adapted to one drawer but it is understood that a plurality of drawers may be similarly disposed therein by suitably enlarging the auxiliary chamber.

Although I preferably provide guide strips 52 to direct the cooling air currents over the top of the drawer, I contemplate that these may be dispensed with and the drawer 54 extend to the chamber side walls as in the aforementioned embodiments and the ports will be controllable by strips slidably positioned on the under side of base 57 and accessible through the main cabinet 3.

Although I have shown and described embodiments of my invention, I contemplate that numerous and extensive departures may be made therefrom without departing from the spirit of

my invention and the scope of the appended claims.

Having thus described my invention, what I claim is:

1. In a refrigerator, an auxiliary compartment adapted to communicate with a main cooling compartment, a drawer disposed within the auxiliary compartment and movable outwardly therefrom in a substantially horizontal plane, rolling elements intermediate the auxiliary chamber and the drawer to effect relative movement therebetween with a minimum of friction, means for sealingly engaging the drawer with the auxiliary compartment when in a closed position, and automatic latch means disposed rearwardly of the inner wall of the drawer for maintaining the drawer in the sealed position, the latch means being rendered inoperable by an outwardly directed pull on the drawer above a predetermined amount.

2. In a refrigerator, a main cabinet having a cooling unit disposed therein, an auxiliary cabinet disposed above the main cabinet, a drawer adapted to be horizontally and sealingly disposed in said auxiliary cabinet, guide means for said drawer spaced from the auxiliary cabinet side walls and generally parallel therewith and extending upwardly substantially to the top of the drawer, and variably controllable ports in the auxiliary cabinet base intermediate the guide means and its corresponding side wall.

3. In a refrigerator, a main chamber having a cooling unit disposed therein adjacent a lateral wall, an auxiliary chamber beneath the main chamber and in communication therewith, means for variably controlling the admission of cooling air currents from the main chamber to the auxiliary chamber and the return of said currents to the main chamber, and a drawer sealingly disposed in the auxiliary chamber and movable outwardly therefrom, said current traversing the drawer from a point of admission adjacent the said lateral wall of the main chamber to a point of return adjacent the opposite lateral wall.

4. In a refrigerator, a main compartment having a cooling unit disposed therein, an auxiliary compartment beneath the main compartment, means variably effecting communication of cooling air currents along a closed path between the compartments, a drawer sealingly disposed within the auxiliary compartment and movable outwardly therefrom, and means disposed at the rear wall of the auxiliary compartment engageable by the drawer automatically latching the drawer in the sealed position upon the drawer reaching a predetermined inward position.

5. In a refrigerator, an auxiliary compartment adapted to communicate with the main cooling compartment, a drawer disposed within the auxiliary compartment and movable outwardly therefrom, latch means disposed rearwardly of the drawer for automatically latching the drawer in sealed position with the auxiliary compartment upon inward movement thereof to a predetermined position, the latch means being rendered inoperable to maintain the drawer in latched position by an outwardly directed pull on the drawer greater than a predetermined amount, and said latch means permitting complete removal and re-insertion of the drawer.

6. In a refrigerator, a main chamber having a cooling unit disposed therein and adjacent the top thereof whereby cooled air will traverse a

downward path to a portion of the cabinet base beneath the cooling unit, thence along the base and upwardly along a lateral wall of the chamber to the cooling unit completing the cooling cycle, an auxiliary chamber beneath the main chamber, means effecting communication of cooling air currents from the main chamber to the auxiliary chamber comprising an entry port in the main chamber base disposed substantially beneath the cooling unit and a return port in said base disposed a substantial distance laterally from the entry port and adjacent a lateral wall of the main chamber, the auxiliary chamber being inaccessible from the main chamber and isolated therefrom except by said ports, and a drawer sealingly disposed in the auxiliary chamber and movable outwardly therefrom with the peripheral portions of the drawer enclosing said ports whereby the cooling air will traverse the drawer.

7. In a refrigerator, a main chamber having a cooling unit therein, a relatively smaller chamber beneath the main chamber, a wall separating the chambers, a hinged closure member for the main chamber, a sliding closure member for the smaller chamber, each chamber being accessible for the removal or insertion of articles only through its associated closure member, an air entry passageway effecting communication

between the chambers disposed substantially beneath the cooling unit, and an air exit passageway disposed a substantial distance laterally of the entry passageway and adjacent a lateral wall of the main chamber whereby cooling air from the main chamber may enter the smaller chamber, traverse the smaller chamber laterally, and return to the main chamber.

8. In a refrigerator, a main refrigerated chamber having a cooling unit disposed therein, a relatively smaller chamber beneath the main chamber, a hinged closure member for the main chamber, a sliding closure member for the smaller chamber, each chamber being accessible through its associated closure member without disturbing the position of the closure member for the other chamber, an air entry passageway effecting communication between the chambers disposed substantially beneath the cooling unit, an air exit passageway disposed a substantial distance laterally of the air entry passageway and adjacent a lateral wall of the main chamber, the chambers being isolated except for said passageways whereby cooling air from the main chamber will enter the smaller chamber, traverse the smaller chamber laterally, and return to the main chamber.

CHESTER A. KUEBLER.
